UNITED STATES PATENT OFFICE.

DARRELL F. DYKE, OF CHICAGO, ILLINOIS, ASSIGNOR TO THE SENG COMPANY, OF CHICAGO, ILLINOIS, A CORPORATION OF ILLINOIS.

THREE-PIECE BED.

Application filed August 3, 1920. Serial No. 400,978.

To all whom it may concern:

Be it known that I, DARRELL F. DYKE, a citizen of the United States, residing at Chicago, in the county of Cook and State 5 of Illinois, have invented certain new and useful Improvements in a Three-Piece Bed, of which the following is a specification.

This invention is particularly designed and intended for use in connection with what is known as a three piece bed, but it is also well adapted for use as a bed rail fastener for other types of bed rails, and as such may be made reversible as well as adjustable to accommodate different bed 10 ends and to make bed ends of the same class practically interchangeable. One of the principal objects of the invention is to provide a bed rail fastener of this kind which is adjustable both laterally and about a limited axis, to provide for bed ends which differ slightly in width, and also to provide 15 for taking up certain differences in alinement due to the warping and the like. Other objects will appear hereinafter. The 20 invention consists in the novel construction, combination and arrangement of the several parts.

In the accompanying drawing, Fig. 1 is a plan view, showing some of the parts in 30 section, of the present invention as embodied in a three piece bed; Fig. 2 is a perspective of one of the fasteners; Fig. 3 is a sectional view of a fastener showing its lateral adjustability with respect to a slotted bed post; Fig. 4 is a perspective of one of the bed 35 rail fasteners which also illustrates the angular adjustability; Fig. 5 is a perspective of a portion of a three piece bed having a wood frame to which the fasteners are 40 readily attached at the ends; and Fig. 6 shows another form of fastener.

A three piece bed commonly comprises a head board, a foot board, and a connecting part in which it is embodied, a mattress, 45 a mattress support, a spring bed bottom or an upholstered bed frame. This connecting part may obviously take a variety of different forms and constructions, and in order to make the connecting part interchangeable with the various head and foot boards, it is necessary that some adjustment be provided in the actual connecting means to allow for any differences in width or variations in angular position.

The present invention provides a bed rail

fastener, one portion of which may be readily attached to a side rail or at the ends of the connecting part, having another piece which is adjustable laterally and at a slight angle to make up for any differences in construction and alinement.

Referring now more particularly to the drawings, the bed ends 6 are each provided with posts 7, which are each formed with a slot 8 extending longitudinally on the 60 inside of the post, across which one or two supporting pins 9 are inserted in a well known manner for engaging the hook of a bed rail fastener. It is desirable that the bed ends be made with these slots 8 spaced 65 exactly the same distance apart in order that the bed ends may be interchangeable and attachable to any connecting member, but in practice this is almost impossible for the reason that the bed ends may warp 70 or swell, or the connecting third piece of the 75 beds may not be uniform, or the side rails of this part may be warped, throwing the bed rail fastener at an angle so that it cannot be inserted in the vertical slot 8.

The connecting member shown in Fig. 1 comprises a frame with angular side rails 10, and braced cross rails 11. The spring fabric A or a mattress construction may be secured to this framework in any desired 80 or suitable manner. At each end of the side rails 10 is a bed rail fastener comprising a plate 12 having a portion 13 bent inwardly at right angles adjacent the end of the rail 10, but spaced slightly therefrom. Above and below the level of the rail 10 are openings 14 which may be rectangular in shape. Attached to the back of the portion 13 is a hook member 15 which has downwardly extending hooks 16 bent 90 and formed out of the material of the hook member and adapted to extend through the openings 14 and to fit loosely therein so that there is considerable play for lateral movement in both directions from a central position. This hook member is attached to the plate 12 by means of a rivet or screw 17, which extends through a transverse slot 18, in the member 15 and into the portion 13 of the plate 12. It will be seen that this connection permits the adjustment of the hooks 16 laterally in the openings 14 and also permits a limited rotating movement about the screw 17 as an axis. As shown in Fig. 3, the hooks 16 may be 110

- laterally adjusted so that they are in alignment with the slot 8 without any movement whatever of the frame to which the bed rail fastener is attached, by simply moving the hook member 15 as desired. The amount of adjustment of course, depends upon the width of the opening 14, but usually a variation or adjustment of several times the width of the slot 8 is all that is required.
- 10 In the construction shown in Fig. 5, the bed rail fasteners 19 are attached at the ends (only one being shown) of a wooden frame comprising side boards 20 and end boards 21 and the slats or cross pieces 22.
- 15 In this type of fastener the lower side of the plate 12 is preferably provided with a bent ear 22 which is adapted to extend below the side board 20 to form an additional support and means for adjustment of the fastener 19. This frame is provided with springs, or a mattress, which may be upholstered in any suitable manner, the bed rail fastener being usually covered so that substantially the fastening hooks only are visible, and as before explained, they can be easily adjusted to fit the slots 8 in the posts, the hook members 15 being manually adjusted to the proper lateral registering position, or angularly, if necessary.
- 20 The connecting member is engaged with the supporting pins 9 by simply inserting the hooks 16 in the slots 8 and pressing them downwardly in engagement therewith. These hooks are formed so that the more firmly they are pressed down, the more tightly they engage the pins 9. It is obvious that these bed rail fasteners are reversible end for end, and also are invertible, the latter requiring, however, that the hook member 15 be inverted by disengaging the fastening screw 17 so that the hooks 16 will extend in the proper direction. In practice this inversion is not ordinarily necessary, and if the end of the side rail 25 to which the bed rail fastener is attached is placed close to the rear face of the hook member 15, as shown in Fig. 3, the screw 17 may be omitted as the hooks 16 will not allow the member 15 to become disengaged from the slots 14 of the plate 12. It is therefore obvious that although this fastener is particularly adapted for use in a three piece bed, it may also be used in any desired position as a bed rail fastener.
- 30 Instead of having the plate of the corner fastening on the outer side of the side board 20, as shown in Fig. 5, a corner fastening 23, as shown in Fig. 6, having the same hook 15, may be formed with two right angled bends 24 and 25, in opposite directions. These bends adapt it to be attached by means of bolts 26 to an end board 27 and by means of fastening devices 28 to the inside end 29 of a side board 30

which projects beyond the end of the end board 27. A supporting lip 31 extends under the end board 27 for additional support. In this construction the outer edge of the corner fastening may be flush with or within the plane of the outer face of the side board, so that it is practically invisible when the bed is assembled, and so that it will present a neat upholstered or covered appearance without in any way interfering with the functions of the corner fastening.

I claim:

1. A fastening device for bed rails comprising an angled plate with perforations in one portion thereof, a member attached to abut the perforated portion, having hooks formed therefrom which are bent at right angles to extend through the openings, the hooks fitting loosely in the openings, so that the member may be adjusted angularly with respect to the plate.

2. In a bed rail fastening device, an angular plate having openings in one portion thereof, a member abutting the inner side of this portion, and having hooks which extend loosely through the openings to the other side thereof, and means for attaching the member to the plate but permitting it to be moved laterally and also angularly for the adjustment of the hooks in the openings.

3. A bed rail fastener adapted to engage spaced supporting pins in the slot of a bed post, the fastener comprising an angularly formed plate with substantially rectangular openings in one portion thereof, a member having hooks formed at right angles thereto, adapted to abut the inner side of the plate with the hooks extending through said openings, the member being formed with a transverse slot intermediate the openings, and a fastening device inserted through the slot and into the plate for attaching the member thereto, but permitting a lateral movement and an angular adjustment of the hooks in the openings.

4. A bed rail fastener comprising an angular plate having openings in one portion thereof, and having an angled extension at the lower side of the other portion thereof, in combination with a hook member attached to abut the inner face of the portion in which the perforations are located, and having hooks formed therefrom at right angles to extend through the openings beyond the other side of this portion, the fastener being attachable to a side rail by means of the other portion of the plate and the fastening extension at the bottom thereof, and the hooks being formed to draw the plate and hook member tightly together when the hooks are operatively engaged.

DARRELL F. DYKE.
